UNITED STATES PATENT OFFICE.

YURAJ DEDIK, OF BOSWELL, PENNSYLVANIA.

RAIL-JOINT.

1,363,574.

Specification of Letters Patent. Patented Dec. 28, 1920.

Application filed February 27, 1920. Serial No. 361,733. Renewed November 24, 1920. Serial No. 426,307.

To all whom it may concern:

Be it known that I, YURAJ DEDIK, a citizen of Czechoslovakia, residing at Boswell, in the county of Somerset and State of Pennsylvania, have invented certain new and useful Improvements in Rail-Joints, of which the following is a specification.

The primary object of the invention is the provision of a rail joint that possesses substantially equal strength to the remainder of the rail when positioned for use upon the roadbed, the joint being readily assembled and disassembled.

A further object of the invention is the provision of a rail joint capable of maintaining its position when the connected rails are secured to the ties without the aid of bolts during the laying of the rails or in a temporary track construction, additional strength however being imparted to the joint by the addition of ordinary bolts.

With these general objects in view and others that will appear as the nature of the invention is better understood the same consists in the novel construction, combination and arrangement of parts hereinafter more fully described, illustrated in the accompanying drawings, and then claimed.

In the drawings forming a part of this application and in which like designating characters refer to corresponding parts throughout the several views,

Figure 1 is an elevational view of the invention with parts broken away,

Fig. 2 is a longitudinal horizontal sectional view taken upon line II—II of Fig. 1.

Figs. 3 and 4 are vertical transverse sectional views taken upon lines III—III and IV—IV of Fig. 1,

Fig. 5 is a perspective view of an attaching end portion of one of the rails,

Fig. 6 is a perspective view of one of the connecting plates employed,

Fig. 7 is a perspective view of the double fish plate construction or rail chair employed with the joint,

Fig. 8 is a side elevation of connected rails showing a slightly modified form of construction upon a reduced scale.

Referring more in detail to the drawings, I have illustrated two rails 10 and 11 with their adjacent ends connected together by my form of joint with the rails in longitudinal alignment as employed in track formation and the adjacent end faces 12 of

the rails slightly spaced apart under normal conditions.

Connecting plates 13 are employed countersunk within cutaway portions or recesses 14 upon the opposite sides of the webs 15 of said rails 10 and 11, receiving grooves 16 being formed in the opposite base flanges 17 of the rails for the sliding reception of the lower edges 18 of said plates 13.

The upper edge 19 of each plate 13 is obtuse angular in shape with the point 20 of the angle centrally of the upper edge of said plate. Receiving slots 16' are provided in the under face of the treads 21 of the rails 10 and 11 within the cutaway portions 14 of the webs 15 thereof opposite and above the receiving grooves 16.

During the assembling of my rail joint, two of the plates 13 are positioned within the grooves 16 and slots 16' of one of the rails such as 11 within the recesses 14 thereof. When the plates 13 are seated within said recesses 14 of one rail, substantially one half of each plate projects outwardly of the end face 12 of the carrying rail permitting said projecting ends of the plates 13 to be slidably inserted in a similar manner within the recesses 14 of the adjacent rail such as 10, the plates 13 at the same time being positioned with the apexes 20 thereof substantially at the adjacent faces 12 of the connected rails as illustrated in Figs. 1 and 2 of the drawings.

A double fish plate or rail chair 22 having a tubular base 23 and opposite fish plates 24 is slidably positioned over the joint formed as above noted and substantially centrally of the connecting plates 13 by sliding the chair 22 longitudinally along one of the rails such as 10 from the free end thereof to the said joint.

The chair 22 having been slidably moved to the position shown in Figs. 1 and 2, securing bolts 25 are positioned through alining perforations 26 in the fish plate portions 24 of the chair and through corresponding perforations 27 in the plates 13 and perforations 28 in the recesses 14 of the rails 10 and 11. Relatively shorter bolts 25' are secured through end perforations 27' in the plates 13 and terminal perforations 28' in the recessed portions 14 of the rail webs 15. In this manner, the plates 13 as well as the chair 22 are secured to the rails 10 and 11 thereby rigidly connecting said rails to

gether. The connected portions of the webs 15 of the rails employing the plates 13 within the recesses 14 render the web portions thereof substantially as strong as the unbroken portions of the webs 15 and taken with the inclosing chair 22 provide a connecting joint possessing great strength and durability. In Fig. 8 the same form of joint is illustrated having however an additional bolt 25' between the plates 13 and the rail webs 15.

While the form of the invention herein shown and described is what is believed to be the preferred embodiment thereof, it is nevertheless to be understood that various forms, modifications and arrangements of the parts may be made without departing from the spirit and scope of the invention as claimed.

What I claim as new and desire to secure by Letters Patent is:—

1. In combination with the adjacent ends of railway rails having recesses at the opposite sides of the webs thereof, and grooves in the base flanges and slots in the treads of the rails at the bottoms and tops respectively of said recesses, connecting plates slidably positioned within said recesses with the upper and lower edges of said plates within said grooves and slots and securing means between said plates and the webs of the connected rails.

2. In combination with the adjacent ends of railway rails having recesses at the opposite sides of the webs thereof, and grooves in the base flanges and slots in the treads of the rails at the bottoms and tops respectively of said recesses, connecting plates slidably positioned within said recesses with the upper and lower edges of said plates within said grooves and slots, a double fish plate slideable upon said rails surrounding the base flanges and webs thereof with fish plate portions flatly engaging said connect-

ing plates and securing bolts transversely 45 positioned through said chair, connecting plates and the webs of the rails.

3. A rail joint comprising identically formed rail ends having oppositely recessed webs with grooves in the base flanges of the 50 rails at the bottoms of the recesses and slots in the lower faces of the treads at the tops of the recesses, connecting plates having angular upper edges, the plates being longitudinally slidable within said recesses with the 55 bottoms of the plates within said grooves and the tops of the plates within said slots, the apexes of the upper edges of the plates being substantially at the abutting end faces of the connected rails when the device is 60 assembled and removable securing means between said plates and rails.

4. A rail joint comprising identically formed rail ends having oppositely recessed webs with grooves in the base flanges of the 65 rails at the bottoms of the recesses and slots in the lower faces of the treads at the tops of the recesses, connecting plates having angular upper edges, the plates being longitudinally slidable within said recesses with the 70 bottoms of the plates within said grooves and the tops of the plates within said slots, the apexes of the upper edges of the plates being substantially at the abutting end faces of the connected rails when the device is 75 assembled, rail chairs having tubular base portions and opposite upright fish plate portions slidable upon the base flanges and webs of said rails positioned centrally of the connecting plates overlying the ends of the rails 80 when the device is assembled with the fish plate portions of the chairs flatly contacting said connecting plates and securing bolts transversely positioned through said fish plate portions of the chairs, said connecting 85 plates and the recessed portions of the rails.

In testimony whereof I affix my signature.
YURAJ DEDIK.
